ACOUSTICAL CORRECTION TILE

William R. Jones and Frank D. Albert, Wabash, Ind., assignors to The Celotex Corporation, Chicago, Ill., a corporation of Delaware

Filed Aug. 24, 1959, Ser. No. 57,261

Term of patent 14 years

We claim:

The ornamental design for an acoustical correction tile,
as shown.
